CLAIM

The ornamental design for an outlet adapter substantially as shown and described.

DESCRIPTION

FIG. 1 is a top perspective view of the present embodiment;
FIG. 2 is a front view of the present embodiment;
FIG. 3 is a rear view of the present embodiment;
FIG. 4 is a right view of the present embodiment;
FIG. 5 is a left view of the present embodiment;
FIG. 6 is a top view of the present embodiment; and,
FIG. 7 is a bottom view of the present embodiment.
The broken lines in the drawings illustrate portions of the
outlet adapter that form no part of the claimed design.
